UNITED STATES PATENT OFFICE

141,704

DESIGN FOR AN EYESHIELD OR SIMILAR ARTICLE

Harry F. Shindel, Reading, Pa., assignor to Willson Products, Inc., Reading, Pa., a corporation of Pennsylvania

Application March 7, 1945, Serial No. 118,313

Term of patent 14 years

(Cl. D57—1)

To all whom it may concern:

Be it known that I, Harry F. Shindel, a citizen of the United States, residing at Reading, in the county of Berks and State of Pennsylvania, have invented a new, original, and ornamental Design for an Eyeshield or Similar Article, of which the following is a specification, reference being had to the accompanying drawing, forming part thereof.

Fig. 1 is a perspective front elevation of an eye-
shield or similar article, showing my new design,

Fig. 2 is a side view of the same, and

Fig. 3 is a front view.

What I claim is:

The ornamental design for an eyeshield or similar article, as shown.

HARRY F. SHINDEL.
